UNITED STATES PATENT OFFICE.

MARTIN ROSSOW, OF DESSAU, GERMANY.

VENEER-DRYING MACHINE.

SPECIFICATION forming part of Letters Patent No. 705,708, dated July 29, 1902.

Application filed November 4, 1901. Serial No. 81,082. (No model.)

To all whom it may concern:

Be it known that I, MARTIN ROSSOW, a subject of the King of Prussia, German Emperor, residing at Dessau, in the Duchy of Saxe-Anhalt, Germany, have invented certain new and useful Improvements in Veneer-Drying Machines; and I do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

15 This invention relates to veneer-drying machines, and has for its object the construction of a machine in which the veneer is fed to endless belts that carry it around heating-cylinders arranged in pairs, one or more pairs 20 of such cylinders with their accompanying endless belts being used for the purpose. The veneer after being passed around the one pair of heating-cylinders is automatically delivered to the next succeeding pair, thereby effecting a complete drying of the wood. These 25 cylinders are preferably heated by steam, and the temperature in all of them may be the same or different, according to the requirements of working.

30 Referring to the drawings, in which like parts are similarly designated, Figure 1 is a longitudinal elevation of such a machine, showing three pairs of drying-cylinders with their endless belts. Fig. 2 is a section on the 35 line X Y of Fig. 1.

I have shown a machine having three pairs of drying-cylinders A B, A' B', and A² B², together with their endless belts a b, a' b', and a² b². The endless belts are arranged so that 40 there will be an upper and a lower belt, both traveling in unison and carrying the veneer between them while passing around the two heating-drums of a pair. These belts are preferably though not necessarily metallic. 45 Each belt is provided with a tension-roller 2, 16, and 32 for the lower series and 15, 25, and 34 for the upper series, respectively, movable to and from the cylinder near which they are located. These tension-rollers may be of any 50 desired construction and are here shown by way of example as mounted on sliding pillow-

blocks that are moved by screws, their specific construction not being embodied in the features of this invention it is believed that further description will not be necessary. 55 The lower endless belt is arranged to project somewhat to the front of the machine, and thereby forms a receiving-table on which the fresh-cut veneer is laid. This belt a passes around roll 1, is preferably though not necessarily slightly inclined upward to roll 3, thus forming the entering or feed table on that portion between these two rolls. The roll 3 is journaled in the frame 37 of the machine and situated close to the lower heating-drum A of the first pair of heating-drums. At about this point it meets the upper belt b, which is next to the cylinder, and the veneer is carried between the two belts and with them around the lower heating-cylinder A, 60 thence to the upper heating-cylinder B, both belts, with the veneer between them, leaving this cylinder at the roll 4. Both belts then travel downward and separate during their travel, the lower belt a passing over the supporting-roll 5 and the roll 6, journaled in the frame of the machine and close to the lower heating-drum A' of the second pair of heater-drums and forming the delivery end of the belt. It then passes from the roll 6 over guide- 65 rolls 7, 8, and 9 to the tension-roll 2 back to the roll 1. The upper belt b of the first pair of heater-rolls meets the lower belt, as stated, at the roll 3, travels around the lower heater-drum A to the upper heater-drum B, roll 4, 70 75 where it leaves said drum, to the roll 11, situated substantially above the roll 6 and journaled in the frame 37 of the machine, at which point it is substantially free from veneer and returns around this roll to the guide-rolls 80 12 13 14 and tension-roll 15 to the feed end of the machine. The veneer is delivered from between the belts at the rolls 6 and 11 to the second pair of endless belts a' b' to be carried around the two heater-drums A' B'. 85 The upper belt b' contacts with the lower heater-drum A', being guided to said drum by the roll 22, journaled in the frame of the machine slightly in advance of the roll 11, so as to be free of the belts a and b. This belt 90 95 then passes around the heater-drum A' and heater-drum B', leaving said drums at the 100

roll 17, thence to roll 23, guide-roll 24, tension-roll 25, guide-rolls 26 and 27, back to the roll 22. The lower belt a' meets the upper belt below the roll 6, and the delivery end of 5 the first pair of belts at about the roll 18, journaled below the roll 6, passes around the heater-cylinder A', together with the upper belt, and thence with it to the upper heater-drum B', the veneer being carried between 10 the two belts, leaving the upper heater-drum B' at the roll 17, passing over guide-roll 50 to the roll 19, which forms the delivery end of the endless belts, thence by guide-rolls 20 21 and tension-roll 16 back to roll 17. This pair 15 of endless belts deliver the veneer in a similar manner to a similar pair of endless belts a^2 b^2 to be carried around another pair of heater-drums A ^{2} B ^{2} . The upper belt b^2 is a short belt and contacts with the first or lower 20 heater-drum A ^{2} , going over roll 33, journaled in the frame 37 of the machine and in advance of roll 23, passing around the drum A ^{2} to the second heater-drum B ^{2} , leaving it at the roll 29, and thence by tension-roll 34, 25 guide-rolls 35 and 36, back to roll 33. The lower belt a^2 travels over roll 28, situated somewhat below roll 19 at the delivery end of the second pair of endless belts, and carries the veneer between it and the upper belt b^2 30 around the drum A ^{2} , the upper drum B ^{2} , guide-rolls 29 30 31, tension-roll 32, back to roll 28. This lower belt b^2 forms a substantially horizontal or slightly-inclined portion between the rolls 29 and 30, which is the delivery 35 end of the machine and from which the veneer is either taken by hand or by an automatic carrier, as may be desired. The drums are geared together in pairs by means of gears g h , i j , k l . The lower drums are 40 driven from one another, and for this purpose each of the lower drums carries a chain-wheel or its substitute (a belt-pulley) l l' l'' and are belted together by belts m' m'' . The machine is driven from the delivery end in any 45 suitable manner, here shown as a gear-wheel m , driving the last lower heater-drum A ^{2} of the series. Power is applied to this lower heater-drum by means of the gear-wheels m n , and motion is transmitted from this lower 50 drum A ^{2} to the upper drum B ^{2} by means of gears k and l , secured to the respective drums. The chain-wheel or belt-pulley l'' transmits motion to the lower drum A' of the second pair of heater-drums by means of the chain 55 or belt m'' . This drum A' transmits motion to the upper drum B' by cog-wheels i j and by the chain-wheel or belt-pulley l' and belt m' on the drum A', which transmits motion to chain-wheel or belt-pulley l on the lower 60 drum A of the first pair of heater-drums.

It will thus be seen that the veneer is fed between the belts and heated first on one side and then on the other by the first pair of heater-drums, then delivered to the second 65 pair of heater-drums and carried between a

second pair of endless belts and also heated first on one side and then on the other, and in like manner delivered to a third pair of endless belts and carried around the heater-drums, to be heated likewise first on one side 70 and then on the other. Referring to Fig. 2, I have shown one of these drums B in section, steam entering by pipe 40, connected to line-pipe 41, and passing through one of the axles and having its exit through the other 75 end of the drum. Suitable cut-off valves are provided by which any one of the drums may be cut out for repairs or other reasons.

An important feature of the invention is the location of the delivery ends of the belts 80 with reference to the entrance to the next succeeding pair of belts, so as to insure the veneer being grasped by the latter, and this is accomplished by having the upper belt descending from above the delivery end of the 85 upper belt preceding it and the lower belt descending toward the drum from the delivery end of the lower preceding belt.

Having thus described my invention, what I claim as new therein, and desire to secure 90 by Letters Patent, is—

1. In a machine for drying veneer, a number of pairs of heater-drums, pairs of carrier-belts passing around both drums of a pair and carrying the veneer between them, each 95 pair of belts arranged to deliver the veneer between the pair of belts of the succeeding pair of drums, substantially as described.

2. In a machine for drying veneer, a number of pairs of heater-drums, pairs of carrier-belts passing around both drums of a pair to carry the veneer between them, each pair of belts arranged to deliver the veneer between descending portions of the next pair of belts and said drums distanced from one another 105 to heat the veneer first on one side and then on the other during its passage through the machine.

3. In a machine for drying veneer, a number of pairs of superposed heater-drums, an upper and a lower carrier-belt to contact with each pair of drums and carry the veneer between them, and deliver it in a downward direction between downwardly-traveling portions of the next succeeding pair of belts at 115 the lower one of the next succeeding pair of drums, means for driving all the lower drums and a gear on each lower and each upper drum, whereby the drums of a pair are geared together. 120

4. In a machine for drying veneer, a number of pairs of superposed heater-drums, an upper and a lower belt passing around each pair of drums, a portion of the lower carrier-belt of the first pair of drums arranged to receive the veneer before meeting the down-coming portion of the upper belt, all the pairs of carrier-belts arranged to deliver the veneer between the down-coming portions of the next pair of belts, said drums distanced from 125 130

one another to heat the veneer first on one side and then on the other, means for driving the lower drums, a gear on each of the lower drums and a gear on each upper drum driven by that on the lower one of a pair of drums, substantially as described.

5 In testimony that I claim the foregoing as

my invention I have signed my name in presence of two subscribing witnesses.

MARTIN ROSSOW.
